UNITED STATES PATENT OFFICE.

GUSTAV F. HAMMER, OF CINCINNATI, OHIO.

METHOD OF TESTING GLOBE-VALVES.

SPECIFICATION forming part of Letters Patent No. 315,276, dated April 7, 1885.

Application filed October 10, 1884. (No model.)

To all whom it may concern:

Be it known that I, GUSTAV F. HAMMER, of Cincinnati, in the county of Hamilton and State of Ohio, have invented certain new and 5 useful Improvements in Methods of Testing Globe-Valves, of which the following is a specification.

My invention has for its object a convenient method of test whereby the valve may be 10 kept at normal temperature while under high steam-pressure.

It is well known that a globe or check valve or stop-cock may be tight when hot and leak when cold, or may be tight under steam-pressure and leak under water-pressure, and that a valve or cock which is proved tight under cold-water pressure will invariably be tight under steam-pressure.

In order to test a valve under cold-water pressure, either a very high natural head is 20 required, which is seldom attainable from city water-mains, or a force-pump, with the consequent labor of attendance and slowness of action, must be employed.

25 In order to supply a cold-water pressure at high heads, say eighty or one hundred pounds, or more, and apply and remove such pressure quickly, is the object of this invention.

The accompanying drawing represents an 30 elevation of an apparatus suitable for carrying out my invention.

A is a globe-valve; B, a steam-pipe connected with a steam-boiler, usually the steam-boiler furnishing power in the factory, (where brass or iron steam-fitters' and plumbers' goods are manufactured.) b is a stop valve or cock in steam-pipe B. C is a water-pipe connected with the city mains, or with an elevated tank. 35 c is a stop-valve in water-pipe C. D D is a system of pipes connecting steam-pipe B and water-pipe C with the T-fitting E. d d' are respectively an elbow and T in the system of pipes D. E is a T provided in its upper run with a nipple, a, to which the valve or stop-cock to be tested is screwed, and in its lower 40

run with a stop cock or valve, F, through which the water is vented after a valve, as A, has been tested.

The operation of the apparatus is as follows: 50 Pipes B and C being connected with the steam-boiler and tank previously mentioned, and a valve or other piece, as A, screwed to nipple a, water is first admitted through valve c to system of pipes D, and consequently to T E and nipple a. (Meanwhile cock F is of course closed.) Cock or valve c is then closed and cock or valve b opened, when steam at boiler-pressure—say eighty pounds, or more—enters 55 system of pipes D and forces the water previously drawn into pipes D against valve A 60 at same pressure. Directly the valve A has been tested cock or valve b is closed and cock F opened, when the contents (water and steam) of pipes D are vented into any convenient sewer or tank connection. The water at 65 normal temperature from pipe C, first filling pipes D, prevents the contact of steam with valve A, and maintains the latter at normal temperature while under steam-pressure of 70 eighty or more pounds.

I do not here claim the apparatus shown and described, as such will constitute the subject-matter of a separate application for Letters Patent.

Having described my invention, what I 75 claim is—

The method herein described of testing valves, which consists in forcing a column of water at normal temperature directly against the valve to be tested, through the medium of 80 steam-pressure behind or in rear of the water-column, substantially as and for the purpose described.

In testimony whereof I have signed my name to the foregoing specification in the presence 85 of two subscribing witnesses.

GUSTAV F. HAMMER.

Witnesses:

CHAS. ANDERSON,
F. LUNKENHEIMER.
